UNITED STATES PATENT OFFICE.

WILLIAM H. WINSLOW, OF CHICAGO, ILLINOIS, ASSIGNOR TO WINSLOW SAFETY HIGH-PRESSURE BOILER CO., A CORPORATION OF ILLINOIS.

ENGINE.

1,150,830.

Specification of Letters Patent. Patented Aug. 17, 1915.

Original application filed April 15, 1911, Serial No. 621,199. Divided and this application filed March 8, 1912. Serial No. 682,427.

To all whom it may concern:

Be it known that I, WILLIAM H. WINSLOW, a citizen of the United States, residing at Chicago, in the county of Cook and State of Illinois, have invented a certain new and Improved Form of Engine, of which the following is a full, clear, concise, and exact description; reference being had to the accompanying drawings, forming a part of this specification.

My invention relates particularly to an improved type of engine construction in which the engine consists essentially of two units so associated that each unit may be independently connected to a driven mechanism and independently control its operating valves, as a result of which the units may have any desired relative rotation. The construction is such, however, that both units are supplied with steam from a common steam chest and subject if desired to common control as starting and stopping.

The engine characterizing my invention is particularly valuable in connection with self-propelled vehicles since each unit may be connected independently to one of the driving wheels and thus exert upon such wheel full tractive effort regardless of the operative condition of the other wheel. When used in this way the steam chest serves in effect to secure all the advantages of a differential gear mechanism without involving any of the disadvantages of such a construction, for the driving force during normal operating conditions is always present ready to be appropriated by the mechanism operating either wheel according to the conditions under which the wheels are operated; a given amount of energy imparted to either wheel is always substantially equal to the different condition, the total amount of energy imparted to the driving mechanism and that imparted to the other wheel. On the other hand,

the action between the motive power and the driven wheels is more elastic than it is possible to secure for any combination of gears without in any way interfering with the effectiveness of operation of the device, and for any practical condition of operation the slippage of one of the wheels does not deprive the other wheel of its driving force, while in the case of differential gearing, to secure effective driving with either wheel

the coefficient of friction of both wheels with the roadway or pavement must be relatively high since the slippage of either wheel deprives the other wheel of its driving force.

The several drawings illustrating my invention are as follows:

Figure 1 is an enlarged rear end view of my improved engine construction. Fig. 2 is a top view of the engine showing its housing and support from the rear axle structure and also partially in section the valves employed to control the operation of the engine pistons. Fig. 3 is a vertical sectional view through the centers of two of the engine cylinders and shows the disposition of the mechanism in the engine casing, and the relation of the parts used to control and reverse the direction of motion of the engine pistons such sectional view being taken along the line 3—3 in Fig. 5. Fig. 4 is a detailed view of the reversing mechanism shown in Fig. 3, removed from the rest of the mechanism to more clearly illustrate its construction and operation. Fig. 5 is a sectional view of a portion of the mechanism shown in Fig. 3, taken along the line 5—5. Fig. 6 is a sectional view of a portion of the mechanism shown in Fig. 3 taken along the line 6—6. Fig. 7 is a sectional view of a portion of the mechanism shown in Fig. 3 taken along the line 7—7. Fig. 8 is a sectional view of a portion of the mechanism shown in Fig. 5 taken along the line 8—8.

Similar numerals refer to similar parts throughout the several views.

As indicated in Fig. 1, the engine casing supports two vertical cylinders 21 and 21^a, which are disposed side by side and extend upward from the axle casing 7; and two horizontal cylinders 22 and 22^a, disposed side by side, and extending forwardly from the axle casing 7. The cylinders 21 and 21^a are, therefore, disposed substantially at 90 degrees to the cylinders 22 and 22^a, and as the cylinders 21 and 22 coöperate to drive one rear wheel of the vehicle while the cylinders 21^a and 22^a coöperate to drive the other rear wheel, it will at once be seen that a means is provided by which each wheel may be driven independently of the other so that the speeds of the two engine units may bear to each other any ratio re-

quired to meet a particular operating condition, and further that each engine unit is always in a condition to start and drive its associated wheel regardless of the angular position of the crank pin driven by such unit.

As shown in Fig. 2, the operation of the cylinders 21 and 21^a is controlled by the cylindrical valves 23 and 23^a, while the operation of the cylinders 22 and 22^a is controlled by the cylindrical valves 24 and 24^a respectively. The valves 23 and 23^a are in communication with the common steam chest 25 supplied with steam by a pipe connection 26, as a result of which either or both of the cylinders 21 and 21^a take steam from the steam chest 25 through the operation of the valves 23 and 23^a according to the conditions under which the wheels 20 driven by the pistons in the cylinders 21 and 21^a are operating, and thus a differential action is secured by means of the common steam chest 25 between the driven wheels of the vehicle without the use of the mechanism of any description, connecting such wheels with each other. The valves 24 and 24^a communicate with a common steam chest 27, having a steam supply pipe 28, by which they control the operation of the pistons in the cylinders 22 and 22^a in a manner similar to that described for the pistons in the cylinders 21 and 21^a. The ends of the bores in which the valves 23 and 23^a operate are connected together, as indicated in Figs. 2 and 3, by a passageway 29 with which an exhaust pipe 30 connects, as indicated in Fig. 3. The valves 24 and 24^a are provided with a similar passage 31 and exhaust pipe 32.

The view shown in Fig. 3 is in addition to being taken along the line 3—3 shown in Fig. 5 taken through the center of the cylinders 21 and 22 and also through the center of the valves 23 and 24, and of the water pump 33, in order to more clearly show the relation of these various parts to the driven and controlling mechanism. As shown in this view the cylinders 21 and 22 are provided with pistons 34 and 35 connected to piston rods 36 and 37, terminating in cross-heads 38 and 39 respectively. Connecting rods 40 and 41 are pivotally connected with the cross-heads 38 and 39, and at their other ends independently engage a common crank pin 42, as more clearly indicated in Fig. 5. The ends of the connecting rods 40 and 41, engaging the crank pin 42 are of comparatively large diameter so as to carry the outer races of ball bearings, the inner races of which are securely clamped upon the crank pin 42 by means of the nut 43. The crank pin 42 is carried by a crank 44 provided with a counter weight 45, as is usual in the art. The crank 44 is mounted upon a crank shaft 46 supported in ball bearings in the 65 casing 6 of the engine, and such shaft has

rigidly secured to it a pinion 47, meshing with the gear 48, rigidly secured to a shaft 49 extending through the axle casing 7 to one of the rear wheels of the vehicle, which is rigidly connected with such shaft 49. A ball bearing is mounted in the casing 6 of the engine to support the inner end of the shaft 49.

A casing 6 supports a spider 50 within it centrally and in a plane extending longitudinally of the device, upon which spider are mounted the parts employed in operating and controlling the valves of the engine cylinders. The spider is provided with a boss 51, extending from both its sides, in which a pin 52 is driven. The projecting ends of the pin 52 have rotatably mounted upon them the eccentrics 53 and 53^a. The eccentric 53 is provided with a forked arm 55 adapted to engage the end of the crank pin 42, and is held in proper position thereon by the grooved collar 56 and the nut 43. The eccentric 53 rotatably engages the ends of the levers 57 and 58 adapted to operate the valves 23 and 24 respectively. The lever 58 is pivotally mounted near its middle portion upon a pin 59 extending from one end of a restraining link 60, the other end of which is pivotally secured to a pin 61, carried by a block 62 mounted upon a curved slide 63 secured at its ends to the spider 50. The other end of the lever 58 is pivotally connected at 64 with a connecting rod 65, pivotally connected at its other end 66 with the outer end of the valve rod 67 connected with the valve 24. The parts described are so proportioned that when the block 62 occupies the position indicated upon the slide 63 the crank shaft 42 will be caused to revolve around to the right, as seen in Fig. 5; and when the block 62 is moved down upon the slide 63 the portion of the stroke during which the admission ports of the cylinder 22 are open is reduced so that cut-off may be obtained at any point desired, and when the block 62 is moved to its extreme lower position, as seen in Fig. 3, the relation of the valve 24 to the piston 35 causes an opposite direction of rotation of the crank pin 42. The valve 24^a is provided with mechanism for actuating it from the crank pin 42^a connected with the piston in the cylinder 22^a, which is identical with that described above for the valve 24; and the block 62 has a pin 61^a projecting from its far side, as seen in Fig. 6 to engage and control the mechanism for the valve 24^a as the mechanism described above is controlled by the pin 61.

The lever 57 is pivotally supported near its middle point upon a pin 68 carried by a restraining link 69, the other end of which is pivotally supported upon a pin 70 carried by a block 71 mounted upon a curved slide 72. The other end of the lever 57 has pivotally connected therewith at 73 the lower

end of a link 74, the upper end of which is pivotally connected at 75 with the lower end of the valve rod 76 connected with the valve 23. This slide 72 is of such conformation 5 and is so placed that when the block 71 occupies the position indicated in Fig. 5 the piston 34 is operated in such a manner as to cause rotation around to the right of the crank pin 42, while motion of the block 71 10 over to the left upon the slide 72 first serves to decrease the length of stroke during which steam is admitted to the cylinder 21, and then for further motion of the block 71 to the left, to reverse the operating condition 15 of the piston 34 in a manner precisely the same as that in which motion of the block 62 upon the slide 63 changes the operation condition of the piston 35. The valve 23^a is provided with operating mechanism 20 actuated by the crank pin 42^a in precisely the manner described above for the mechanism involved in the operation of the valve 23; and the block 71 has extending from its far side, as seen in Fig. 3, a pin 70^a, as 25 shown in Fig. 7, operating when the block 71 is moved on the slide 72 to control the relation of the valve 23^a to the piston contained in the cylinder 21^a in precisely the same manner that such motion of the block 30 71 controls the relation of the valve 23 to the piston 34. A bell-crank 77 is pivotally mounted upon a pin 78 carried by the spider 50, the left hand end of such bell-crank being connected by a link 79 with the pin 61 35 of the block 62, while the right hand end of such bell-crank is connected by a link 80 with the pin 70^a carried by the block 71. The bell-crank 77 and the links 79 and 80 are so proportioned that motion of the bell- 40 crank serves to move the blocks 62 and 71 simultaneously upon the slides 63 and 72, so that the same relation is maintained between the valves 24 and 24^a and their associated pistons that exists at any time between the 45 valves 23 and 23^a and their associated pistons. The right hand end of the bell-crank 77 is also connected by a link 81 with a collar 82 screwed on to the right hand end of the tube 83, extending to the left through a 50 tubular extension 84 formed on the casing 6. The collar 82 is maintained in proper position upon the tube 83 by means of the jam nut 85, and the tube 83 has secured to it outside of the portion 84 of the casing a collar 86, between which and the end of the tubular portion 84 a tension spring 87 is 55 located. The tube 83 contains within it a rod 88 supported within a casing 6 by lugs 89 and 90 formed thereon. Just to the left 60 of the lug 89 a collar 91 is secured to the rod 88 in a position to be engaged by the right hand end of the tube 83, and between the lugs 89 and 90 a second collar 92 is secured to the rod 88 to be engaged by the 65 left hand end of the compression spring 93, 70 extending between such collar and the lug 90. The spring 87 is constructed of such a strength as to move the blocks 62 and 71 as far up and to the right respectively on their corresponding slides as the position of the rod 88 will permit. For the position of such rod indicated in the drawings, such blocks and the parts carried thereby are moved to the position indicated, which allows the pistons to take steam from the steam chests for 75 their full stroke in each direction. This represents the condition of operation when the maximum possible power of the engine is required, although it will be understood that the engine at this time is not working as efficiently as for other relations of the valve mechanism. The spring 93, which is constructed so as to be considerably stronger than the spring 87, moves the rod 88 to the left until the collar 92 engages the lug 89, 80 85 which prevents further motion of the rod 88. For this motion the collar 91 secured to the rod 88 moves the tube 83 to the left sufficiently to rotate the bell-crank 77 around to the left, as seen in Fig. 3, to move the blocks 90 62 and 71 to a position giving the most effective running condition of the engine in a forward direction, which position is commonly referred to as the "hook-up" position. For this condition the admission 95 ports of the engine are closed at such a portion of the stroke that the full value of the steam admitted is employed expansively in the cylinders.

From the description given above it will 100 appear that each of the crank pins 42 and 42^a is entirely independent from the other and that the mechanism supported thereby bears no relation whatever in its operation to the mechanism controlled by the other 105 crank pin, and further that each crank pin directly controls the valve mechanism of the two cylinders employed to operate it by means of a single eccentric and that the two independent engine units thus formed are 110 controlled simultaneously both as to reversal, and the point of cut-off for either direction of motion by a single actuating mechanism of simple construction regardless of the position of the mechanism of one engine unit relatively to the mechanism of the 115 other unit.

The water pump 33 carried by the casing 6 is provided with a plunger 94 pivotally connected at its right hand end with a connecting rod 95, which rod at its right hand end is engaged by a pin 96 eccentrically carried by the left hand end of the shaft 49^a, 120 as seen in Fig. 5. The casing 6 also carries an air pump 98, the piston 99 of which is 125 pivotally connected with the upper end of the connecting rod 100, the lower end of which engages a pin 101 carried by the connecting rod 40^a of the cylinder 21^a. As a 130 result of the connections described when the

engine is operated the pumps 33 and 98 are actuated in a manner well known in the art to feed water to the boiler and compress the air in the fuel tank.

- 5 The casing 6 is provided with a cover-plate 102 on its rear wall, by removing which access may be readily had to all of the mechanism contained within such casing, and if desired for purposes of inspection or
 10 repair, the spider 50 and all of the controlling mechanism carried thereby may be removed from the casing in assembled condition by releasing the connections holding the spider in place when the crank pins 42 and
 15 42^a are in their lowermost position and the link 81 and the valve connecting rods are disconnected. The casing 6 is completely inclosed, and may if desired contain oil to thoroughly lubricate the moving parts.
 20 Caps as shown at 103 and 104 are provided in connection with the cross-heads to constitute an extra protection for the piston rods of the engine.

In connection with the description of the
 25 valve controlling mechanism given above and the drawings illustrating the same, it will be noted that the parts supported by the spider 50 are held in place thereon by the relation of the links to each other and to the
 30 eccentrics controlling them and that these parts are held in place by the engagement of the forked ends of the arms extending from the eccentrics 53 and 53^a with the corresponding crank pins, thus making it a com-
 35 paratively simple matter to separate the eccentrics from the corresponding levers and to remove the parts from the supporting pins carried by the spider when it is desired to separate the parts from each other.

- 40 The surface of the spider 50 may be finished on both its sides, or if desired only portions thereof may be finished to be engaged by the links of the controlling mechanism, as indicated for the restraining links 69 and
 45 69^a shown in Fig. 7. It is to be noted, however, that only such parts of the apparatus come in sliding engagement with the surface of the spider 50 as are normally at rest or moved but very little, as a result of which
 50 the wear upon such parts is practically negligible.

While the pumps 33 and 98 are shown as operated by the same engine unit, it is to be understood that either unit may be employed for this purpose, or that either unit may operate either pump in any suitable manner, without departing from the spirit of my invention.

- 55 From the description given above of the operation of the common steam chest in connection with two engine cylinders of different units, it will be understood that although differential gearing is entirely eliminated, the engine construction affords what is many
 60 ways similar results. That is, the driv-

ing force during normal operating conditions is always present, ready to be appropriated by the mechanism operating either wheel according to the conditions under which the wheels are operating; and again, 70 the amount of energy imparted to either wheel is always substantially equal to the difference between the total amount of energy imparted to the driving mechanism and that imparted to the other wheel. On the other hand, the connection between the motive power and the driven wheels is more elastic than it is possible to secure with any combination of gears without in any way interfering with the effectiveness of operation 75 of the device, and for any practical condition of operation the slippage of one of the wheels does not deprive the other wheel of its driving force, while in the case of differential gearing to secure effective driving with either wheel the coefficient of friction of both wheels with the roadway or pavement must be relatively high, since the slippage of either wheel deprives the other wheel of its driving force. 80

90 While the gears 48 and 48^a may if desired have the same number of teeth and be of the same diameter, it is preferable to have the number of teeth different. For instance, the gear 48 may have 54 teeth while the gear 48^a is provided with 55 teeth, as a result of which the possibility of the two sections of the engine keeping in step with each other will be prevented, and thus the building up of the vibration tendency of the two parts of the engine, due to the simultaneous thrust in the same direction of the parts of the two sections of the engine which may be unequally distributed, is avoided. In this way the wear and jar on the moving parts and the housing is reduced to a minimum. 95 100 105

The present application is a divisional application of my co-pending application serial No. 621,199, filed April 15, 1911. 110

Many changes in the mechanism disclosed may be employed without departing from the spirit of my invention, and I, therefore, desire to claim broadly all mechanical equivalents that may suggest themselves to those skilled in the art. 115

What I claim is:

1. In combination, an automobile engine comprising a pair of cylinder castings secured to each other, said castings bearing two pairs of cylinders arranged at 90 degrees to each other, a steam chest in each cylinder casting, side plates secured to said cylinder castings, a separate crank-shaft having a bearing in each side-plate, a pair of quartered pistons connected to each crank-shaft, said pistons working in said cylinder, a removable plate arranged in a median line between said crank-shafts in said cylinder castings, valve mechanism 120 125 130 135

mounted on said plate, and a common load for both of said crank-shafts.

2. In an engine, the combination of two independent engine units, each unit comprising a pair of quartered cylinders, a crank-shaft for each unit, said shafts being coaxial and connected to each other through the load only, a valve gear for each cylinder, a single valve eccentric for each unit, and a removable plate secured to both units, said plate supporting said eccentric and the valve gear of each unit.

3. In combination, a pair of crank-shafts for transmitting motion to a common load at variable rates of speed, a separately-operating engine connected to each of said crank-shafts, said engines being secured together by a common casing, a common steam chest adjacent the valve chambers of said engines, and shiftable valve mechanism for simultaneously adjusting the cutoff of both engines.

4. In combination, a pair of coaxial shafts connected to the driving wheels of a vehicle, separate cranks attached to said shafts, a casing forming supporting means for said shafts surrounding said cranks, a pair of quartered cylinders for each crank, mounted on said casing, said cylinders being arranged in V formation and having a steam chest for each pair of cylinders communicating with the valves, and shiftable valve mechanism for simultaneously adjusting the cutoff for all of said cylinders.

35 5. In combination, a pair of coaxial shafts connected to the driving wheels of a vehicle, a separate crank for each shaft, a horizontal and a vertical cylinder for each crank, a casing supporting the ends of said shafts and forming a base for said cylinders, said horizontal cylinders arranged in pairs, and said vertical cylinders arranged in pairs, a steam chest for each pair of cylinders, said cylinders having valves communicating directly with said steam chest.

6. In combination, a pair of coaxial shafts arranged end to end, said shafts connected at their outer ends to the driving wheels of a vehicle and adapted to travel at various relative rates of speed, a separate crank for each shaft, a pair of quartered cylinders for each crank, said cylinders of the two engines being arranged parallel in pairs, a common steam chest for each pair of cylinders,

ders, and common valve-shifting mechanism 55 for adjusting the cutoff similarly on all the cylinders regardless of the relative speeds of the shafts.

7. In an engine, the combination of a single housing, two engine units mounted in the housing so that each may move independently of the other, independent driving shafts for said units, said shafts both operating upon a common load but at different relative rates of speed, and means for 65 simultaneously varying the cutoff of the valves of both units.

8. In an engine, the combination of a single housing, two engine units mounted in the housing so that each may operate relatively independently of the other, a common steam chest for said units, said steam chest allowing different amounts of work to be done by each unit for a given throttle opening, a common load driven at different 70 relative speeds simultaneously by said units, and means for simultaneously varying the cutoff of both units.

9. In a vehicle engine, a pair of shafts adapted to be connected to the driving 80 wheels of the vehicle, an independently-operating engine unit for each shaft, each unit comprising a pair of quartered cylinders having pistons operating on a common crank, a common steam chest for a cylinder 85 of each unit, independently-operating valve mechanism, and common reversing means for the valve mechanism of each unit.

10. In combination, a vehicle engine, a pair of coaxial shafts adapted to be connected to the driving wheels of the vehicle, said engine comprising a pair of units, each of said shafts being connected to one of said units, each unit comprising two cylinders angularly disposed relative to each other, 95 a single eccentric for controlling the valves of each unit, and means for controlling said units simultaneously by a single actuating mechanism, regardless of the position of the mechanism of one unit relative to the mechanism of the other unit.

In witness whereof, I hereunto subscribe my name this 29th day of February, A. D., 1912.

WILLIAM H. WINSLOW.
